UNITED STATES PATENT OFFICE.

ROSS M. BRASINGTON, OF MARIETTA, OHIO.

COMPRESSOR REGULATOR.

Application filed August 22, 1922. Serial No. 583,481.

To all whom it may concern:

Be it known that I, ROSS M. BRASINGTON, a citizen of the United States, residing at Marietta, in the county of Washington and 60 State of Ohio, have invented new and useful Improvements in Compressor Regulators, of which the following is a specification.

The object of my said invention is to improve compressor regulators by the provision 10 of means sufficiently strong to overcome the friction caused by the needle valve sticking in its seat and to raise the said valve when a certain predetermined pressure is attained.

To the attainment of the foregoing, the 15 invention consists in the improvement as hereinafter described and definitely claimed.

In the accompanying drawings, forming part of this specification:—

Figure 1 is a vertical section of a compressor regulator embodying my improvement.

Figure 2 is an enlarged detail section showing a slight modification of my invention.

Figure 3 is a horizontal section taken in the plane indicated by the line 3—3 of Figure 2, looking downwardly.

The compressor regulator illustrated comprises in its upper portion a casing 1 having 30 an arm 2 for connection with a compressor and also having relief means 3. The arm 2 is in communication with a chamber 4, and the relief means 3 is in communication with a chamber 5 below which is a piston cylinder 6 and a spring pressed piston 7. The lower part of the construction of the compressor may be as illustrated in Figure 1 or 35 may be similar in construction to the compressor regulator disclosed in the patent to one Wainwright 1,366,853 of January 25, 1921. It will also be noted by reference to Figure 1 that a piston 8 is movable in the casing 1 and is backed by a spring 9 which in turn is backed by a screw 10 threaded in 40 the upper end portion of the casing. This structure is common to that of the patent cited as is also the apertured valve seat 11 by which communication is effected between the chambers 4 and 5.

Carried by the piston 8 and extending 50 downwardly therefrom is a needle valve 12 for cooperation with the valve seat 11. The said needle valve 12 is preferably headed at 13 and secured to the piston 8 through the 55 medium of an annular nut 14 as illustrated.

In accordance with my invention a coiled

spring 15 is interposed between the piston 8 and the bottom wall of the chamber 4, the said spring 15 being shown in the illustrated embodiment as bearing against the nut 14 which is flanged at its lower end.

My novel spring 15 is preferably cone shaped and is designed to exert at all times an upward pressure on the piston 8. The said spring 15 is considerably weaker than 65 the tension spring 9, but is sufficiently strong to overcome the friction due to the tendency of the needle valve 12 to stick in its seat. The practical advantage of the spring 15

70 relatively arranged as described will be better understood when it is stated by way of example that when it is desired to carry ninety pounds of air pressure, and the needle valve is seated until said pressure is attained, the needle valve instead of unseating at said 75 time will require for its unseating a number of pounds in excess of the desired pressure which is very objectionable as is well known to those skilled in the art. In virtue of my improvement the spring 15 serves to 80 open the needle valve when the desired pressure is attained, and this promptly so that the apparatus is rendered extremely sensitive.

The spring 15 is so made that when valve 12 is in its upper position, spring 15 is in 85 a neutral state. It does not necessarily engage the valve 12 in its extreme upper position. During the descent of valve 12 to its seat, the resistance opposed by spring 15 is 90 at first zero and is but slight until valve 12 nears its seat and is accumulated within a short range of movement until its maximum is reached as valve 12 reaches its seat. The resistance of spring 15 to the seating 95 movement of valve 12 is overcome by spring 9 aided by the momentum imparted to valve 12 while that resistance was zero or small. The useful action of spring 15 is to prevent jamming of valve 12 by its momentum when seating and when the air pressure falls below 100 that for which spring 9 is adjusted. Should valve 12 leave its seat at a lower pressure than that for which spring 9 is adjusted, the effective pressure of spring 15 would 105 soon be lost and the spring 9 would return the valve to its seat, upon small further reduction of pressure due to its opening, and little air would escape from the receiver in consequence. Experience shows that the operation of the regulator is not materially affected by any such opening of valve 12 at

110 too low pressures.

When deemed expedient the spring 15 may be connected to the lower end of the piston 8. The connection alluded to may be and preferably is effected by extending the upper 5 terminal 15^x of the spring 15 through a diametrical aperture 16^x in the needle valve 12, and the connection is advantageous inasmuch as when the piston 8 is removed from the casing, the spring will be removed with it.

10 Irrespective of whether the spring 15 is connected with the piston 8 or not I prefer to have the lower end of the spring smaller than the inside dimension of the chamber walls of the piston 8 so that the spring can 15 be inserted without scratching or marring the said wall or walls. I also prefer to taper the spring as illustrated so as to obviate the liability of the spring leaning to one side or the other.

20 I have entered into a detailed description of the construction and relative arrangement of the parts embraced in the present and preferred embodiments of my invention in order to impart a full, clear and exact understanding of the said embodiments. I do not desire, however, to be understood as confining myself to the specific construction and relative arrangement of parts inasmuch as in the future practice of the invention various changes and modifications may be 25 made such as fall within the scope of my appended claims.

Having described my invention, what I claim and desire to secure by Letters- 30 Patent, is:—

1. In a compressor regulator, the combination with a casing having a chamber for connection with a compressor, a chamber for connection with a piston cylinder, an apertured diaphragm between said chambers, a piston in communication with the first-named chamber, a spring backing said piston, and a valve carried by said piston and adapted to seat in said apertured diaphragm; of a spring weaker than the first-named spring surrounding the valve and interposed between the apertured diaphragm and the spring-backed piston.

2. In a compressor regulator, the combination with a casing having a chamber for

connection with a compressor, a chamber for connection with a piston cylinder, an apertured diaphragm between said chambers, a piston in communication with the first-named chamber, a spring backing said piston, and a valve carried by said piston and adapted to seat in said apertured diaphragm; of a spring weaker than the first-named spring surrounding the valve and interposed between the apertured diaphragm and the spring-backed piston; the said interposed spring being tapered upwardly. 55

3. In a compressor regulator, the combination with a casing having a chamber for connection with a compressor, a chamber for connection with a piston cylinder, an apertured diaphragm between said chambers, a piston in communication with the first-named chamber, a spring backing said piston, and a valve carried by said piston and adapted to seat in said apertured diaphragm; of a spring weaker than the first-named spring surrounding the valve and interposed between the apertured diaphragm and the spring-backed piston; the said interposed spring being tapered upwardly. 60

3. In a compressor regulator, the combination with a casing having a chamber for

connection with a compressor, a chamber for connection with a piston cylinder, an apertured diaphragm between said chambers, a piston in communication with the first-named chamber, a spring backing said piston, and a valve carried by said piston and adapted to seat in said apertured diaphragm; of a spring weaker than the first-named spring surrounding the valve and interposed between the apertured diaphragm and the spring-backed piston; the said interposed spring being tapered upwardly. 65

4. In combination, an unloader valve for fluid compressors having a casing formed with a pair of chambers, an apertured diaphragm between said chambers, a piston mounted for reciprocation in one of the cylinders, an expansion spring behind said piston for normally forcing it toward the diaphragm, and a pin valve carried by the piston for projecting into the aperture in the diaphragm for closing said aperture against the passage of fluid between the chambers; and a spring surrounding said pin and interposed between the diaphragm and piston for overcoming the sticking action of the pin in the aperture when the pressure of the fluid in the chamber is sufficient to overcome the pressure of the first-mentioned spring for moving the piston and unseating the pin from the aperture. 70

4. In combination, an unloader valve for

fluid compressors having a casing formed with a pair of chambers, an apertured diaphragm between said chambers, a piston mounted for reciprocation in one of the cylinders, an expansion spring behind said piston for normally forcing it toward the diaphragm, and a pin valve carried by the piston for projecting into the aperture in the diaphragm for closing said aperture against the passage of fluid between the chambers; and a spring surrounding said pin and interposed between the diaphragm and piston for overcoming the sticking action of the pin in the aperture when the pressure of the fluid in the chamber is sufficient to overcome the pressure of the first-mentioned spring for moving the piston and unseating the pin from the aperture. 75

4. In combination, an unloader valve for

fluid compressors having a casing formed with a pair of chambers, an apertured diaphragm between said chambers, a piston mounted for reciprocation in one of the cylinders, an expansion spring behind said piston for normally forcing it toward the diaphragm, and a pin valve carried by the piston for projecting into the aperture in the diaphragm for closing said aperture against the passage of fluid between the chambers; and a spring surrounding said pin and interposed between the diaphragm and piston for overcoming the sticking action of the pin in the aperture when the pressure of the fluid in the chamber is sufficient to overcome the pressure of the first-mentioned spring for moving the piston and unseating the pin from the aperture. 80

4. In combination, an unloader valve for

fluid compressors having a casing formed with a pair of chambers, an apertured diaphragm between said chambers, a piston mounted for reciprocation in one of the cylinders, an expansion spring behind said piston for normally forcing it toward the diaphragm, and a pin valve carried by the piston for projecting into the aperture in the diaphragm for closing said aperture against the passage of fluid between the chambers; and a spring surrounding said pin and interposed between the diaphragm and piston for overcoming the sticking action of the pin in the aperture when the pressure of the fluid in the chamber is sufficient to overcome the pressure of the first-mentioned spring for moving the piston and unseating the pin from the aperture. 85

4. In combination, an unloader valve for

fluid compressors having a casing formed with a pair of chambers, an apertured diaphragm between said chambers, a piston mounted for reciprocation in one of the cylinders, an expansion spring behind said piston for normally forcing it toward the diaphragm, and a pin valve carried by the piston for projecting into the aperture in the diaphragm for closing said aperture against the passage of fluid between the chambers; and a spring surrounding said pin and interposed between the diaphragm and piston for overcoming the sticking action of the pin in the aperture when the pressure of the fluid in the chamber is sufficient to overcome the pressure of the first-mentioned spring for moving the piston and unseating the pin from the aperture. 90

4. In combination, an unloader valve for

fluid compressors having a casing formed with a pair of chambers, an apertured diaphragm between said chambers, a piston mounted for reciprocation in one of the cylinders, an expansion spring behind said piston for normally forcing it toward the diaphragm, and a pin valve carried by the piston for projecting into the aperture in the diaphragm for closing said aperture against the passage of fluid between the chambers; and a spring surrounding said pin and interposed between the diaphragm and piston for overcoming the sticking action of the pin in the aperture when the pressure of the fluid in the chamber is sufficient to overcome the pressure of the first-mentioned spring for moving the piston and unseating the pin from the aperture. 95

4. In combination, an unloader valve for

fluid compressors having a casing formed with a pair of chambers, an apertured diaphragm between said chambers, a piston mounted for reciprocation in one of the cylinders, an expansion spring behind said piston for normally forcing it toward the diaphragm, and a pin valve carried by the piston for projecting into the aperture in the diaphragm for closing said aperture against the passage of fluid between the chambers; and a spring surrounding said pin and interposed between the diaphragm and piston for overcoming the sticking action of the pin in the aperture when the pressure of the fluid in the chamber is sufficient to overcome the pressure of the first-mentioned spring for moving the piston and unseating the pin from the aperture. 100
